LINE CASTING MACHINE

Charles J. Rubb, Flushing, N. Y.

Application February 6, 1940, Serial No. 317,508

8 Claims. (Cl. 199—52)

My invention relates to improvements in typecasting machines and more particularly to means for automatically stopping said machine after a definite interval or operation.

- 5 One object of my invention is to provide means which will automatically stop a typecasting machine, if said machine remains idle for a predetermined length of time, or will stop a typecasting machine after the completion of a certain 10 operation or movement of said machine. The main object is not only saving wear and tear on the machine and motor, but the saving in current of both motor and the light over the key board.
- 15 The present means may be applied to two different types of machines, that is, the Linotype or Intertype type of machine or any other linecasting and composing machines which utilize circulating matrices, and the Ludlow machine in 20 which the matrix is set by hand and inserted into the machine, whereafter the slug or line is automatically cast.

In large composing rooms, especially for newspapers and magazines where many Linotype or 25 Intertype machines are used, machines are left running idly due to operators changing from one machine to another—sometimes for hours. To remedy this, my invention will automatically stop the machine and turn off the attached light for 30 any idle interval from one-half (½) a minute to any other time designated, after the operator has cast his last line. The operator in no way takes any part in this. The operator starts his machine as usual by pressing a switch; after that, as long 35 as he continues to set slugs, my device keeps the machine running.

Another object of my invention is to provide simple means which will automatically stop a composing machine if the time between the casting of successive lines is greater than a certain predetermined time.

In the present type of Ludlow machine, the operator sets the matrix in a form and inserts the same into the machine. He then steps on a 45 footswitch starting the motor and next presses the tripping lever which starts the linecasting operation. During the entire operation, the operator must keep his foot on the footswitch, thus preventing him from doing anything else.

50 My invention, on the Ludlow machine, does away with the turning on of a switch or having to step on a footswitch before the operator presses the tripping lever to make a line. All the operator does now, is press the tripping lever for a 55 second or two and he can leave the machine to

do whatever else he has to do. After the machine has cast the line, the motor will automatically stop.

Another object of my invention is to provide means of the character above set forth which may be conveniently and simply attached to the standard forms of typecasting machines without interfering with the operation thereof.

Other objects of my invention will be set forth in the following description and drawings which 10 illustrate preferred embodiments thereof, it being understood that the above statement of the objects of my invention is intended to generally explain the same without limiting it in any manner.

Fig. 1 is a side view of the rear of an Intertype machine showing my device attached thereto.

Fig. 2 is a fragmentary front view of the top part of the resetting shaft.

Fig. 3 is a front view of the control switch- 20 board.

Fig. 4 is a partial side view of a Ludlow machine showing one of the switches of my device and the control cam therefor.

Fig. 5 is a partial front view of a Ludlow ma- 25 chine, showing the tripping lever, control cam, and two switches of my device.

Fig. 6 is a circuit diagram of the switch circuit in the Intertype machine.

Fig. 7 is a circuit diagram of the switch circuit 30 in the Ludlow machine.

Referring to the drawings, and more particularly to Figs. 1, 2 and 3, I have shown my device attached to an Intertype machine. A time switch T is secured to bar 1 by means of bolts 2 passing 35 through the casing 3 of time switch T and the vertical arm of bar 1. Bar 1 in turn is bolted by means of bolts 4 to any rigid part of the machine and in such a position that the switch or bar in no way interferes with any moving parts or the 40 operation of the machine.

The parts of the Intertype machine which are shown in the drawings, and are well known and whose functions require no explanation are first elevator cam 5, roller 6 rotationally mounted by 45 means of pin 7 to lever 8, said roller contacting the cam surface of cam 5, and parts of the second elevator mechanism consisting of shaft 9, lever 10, arms 11 and 12 and bearing arm 13. However, it is important to note that arm 12 50 oscillates clockwise and counterclockwise through a small arc, said oscillation commencing at the completion of each casting operation and at the start of the lifting of the matrices to the matrix distributor.

The time switch consists of a mercury contact 14 held by clamp member 15, which clamp member is pivotally mounted by means of pin 18 between plate 19 and face 21 of casing 3. Plate 19 is secured to the wall 21 of the escapement movement 22 by means of screws 20. Rigidly attached to clamp member 15 and rotating therewith is the arm 16, said arm terminating in a substantially V-shaped notch 17, said notch having its lower arm longer than its upper arm. The opening and closing of the mercury contact 14 is controlled by the plunger device P and timing mechanism 22.

The plunger P comprises a vertical shaft 23 having a series of transverse teeth 25 cut along the length of said shaft. Depending from the bottom of shaft 23 is weight 24, said weight having a concave depression formed in its bottom face and a felt washer positioned on its top face. The shaft 23 is slidably mounted through the timing mechanism 22, said timing mechanism being well-known and old in the art, and being of the escapement or any other known type, and allowing the said shaft to freely pass upwardly but retarding its downward motion. The time which it takes the plunger to reach its lowest position from its topmost position depends on the length of the shaft 23 and the retarding action of the timing mechanism 22. Secured to the top of shaft 23 is a horizontal arm 26, said horizontal arm being adapted to engage the V-shaped slot 17 of the arm 16. Leads 27 lead from the electrodes of the mercury contact to terminals 28 secured to the side wall of the casing 3, and leading from said terminals through BX cable 30 are conductors 29, said BX cable being coupled to the bottom wall of the casing 3 by means of coupling 31. Plunger P is reset to its topmost position shown in dotted lines in Fig. 1 by arm 12 when arm 12 swings clockwise, which event occurs when the matrix is lifted from the casting mechanism to the distributor. Secured to the outer end of arm 12 is a knob 32, which knob engages the concave surface 21 of the weight 24. Fig. 3 is a front view of the switchboard showing three switches 33, 34 and 35, switch 35 being merely a signal switch and being unrelated to the present invention. Switch 34 (referring also to Fig. 6) is a main switch which connects the entire circuit to a source of current. Switch 33 is a time switch of any known kind which, when closed, will automatically open in about three minutes, thus giving the operator time to get set.

This device operates as follows: The operator closes switch 34 and then closes switch 33, thus starting the motor M and giving him three minutes within which to complete the first line. If he does not complete a line within the initial three minutes, switch 33 will automatically open and since time switch T has not been brought into operation the motor M will stop. On the other hand, if he completes a line within the first three minutes, the elevator will come into operation and arm 12 will rotate to its topmost position and thus close the mercury contact 14. The time within which he must complete his next line depends upon the length of time it takes plunger P to reach its lowest position thus tripping arm 16 and opening contact 14.

As already stated, the time within which the mercury contact remains closed may be regulated and should be between a minute and a minute and a half.

The present means may also be applied to a

Ludlow machine and, although the same circuit be used, there is no time switch involved.

Referring to Fig. 4, 48 designates a side of a Ludlow type machine and 41 the drive shaft of said machine. Rotationally rigid with said drive shaft is the disk cam member 39 having a depression 40 formed in its peripheral face. Secured to the side of said machine and situated above said cam disk 39 is a switch 36, said switch being operated by means of a lever 37 having a roller 38 pivotally mounted at the end of said lever 37 by means of a pin 49. The switch 36 is in closed position when lever 37 is in the position designated by the dotted lines and said switch is in open position when the lever is at 15 its lowermost point.

Referring now to Fig. 5, 51 is the front of a Ludlow type machine having the tripping lever 42 pivotally mounted by means of pin 43 to the upper part of said front 51 and situated below said lever is a locking device 44. When tripping lever 42 is rotated slightly in a clockwise direction, the clutch between the drive shaft 41 and the electric motor operating said Ludlow machine is engaged. Located at the side of front member 51 and directly below tripping lever 42 is switch 45 having a knob or peg 46 projecting from the top thereof and falling directly beneath one arm of the tripping lever. When the peg is in its topmost position, switch 45 is open and when 46 is in the position indicated by the dotted line 46' the switch 45 is in closed contact. Leading from the bottom of switch 45 to an ordinary throw switch 47 is the BX cable 52.

Referring now to Fig. 7 which is a circuit diagram of the Ludlow machine, 36, 45 and 47 represent the same switches as were above set forth.

The Ludlow machine just described operates as follows: The operator sets his matrix and inserts it into the machine and after having closed switch 47 he then presses tripping lever 42, to the position shown by the dotted line 42'. This performs two things: It causes the clutch between the drive shaft 41 and the motor to be engaged and closes switch 45, thus starting up such motor. When shaft 41 rotates, cam 39 rotates therewith thus bringing depression 40 from the position shown to the position shown in dotted line 40', thus causing lever 37 to rotate about to its topmost position and closing switch 36. The operator momentarily depresses the tripping lever 42 only to start the casting operation and thereafter releases the said lever 42 thus causing switch 45 to return to its normally open position. The complete casting of the line or slug requires merely one rotation of shaft 41 and, therefore, when the cam 39 has rotated 360 degrees from its initial position, roller 38 will fall back into the depression 40, thus opening switch 36 and thus stopping the motor. In order to start this operation again, all the operator need do is press tripping device 42.

I have illustrated my device as used on an Intertype and Ludlow type of machine but it is quite obvious that it may be applied to any similar type of machine such as Linotype machines, etc.

I have shown preferred embodiments of my invention but it is apparent that numerous changes and omissions may be made without departing from its spirit. For example, where I have shown one type of switch such as a lever switch another type may be substituted therefor such as a plunger switch. Secondly, I have shown some of my switches placed in certain positions

and controlled by certain operations or movements of parts of the machine but it is obvious that these switches may be situated at other points where they will not interfere with the operation of the machine and may be controlled by any other permissible or applicable movement of other parts of the machine.

I claim:

1. In a Ludlow type of line casting machine having an electric motor as motivating means, a pair of parallel switches intermediate the source of current and said electric motor, one of said switches being controlled by the tripping lever of said machine, the other switch being controlled by a moving part of the machine.

2. In a Ludlow type of line casting machine having an electric motor as motivating means, a pair of parallel switches intermediate the source of current and said electric motor, one of said switches being normally open and being adapted to being closed while the tripping lever of said machine is depressed, the other switch being manipulated by an arm extending from said switch, said arm being controlled by a cam, which cam is rotationally rigid with the drive shaft of said machine.

3. A device as claimed in claim 2 in which the arm manipulated switch is in open position only when the free end of said arm is in contact with the low point of said cam, said low point being in contact with the free end of said arm only at the commencement and termination of the line casting operation.

4. In a machine of the circulating matrices type, having an electric motor as its motivating means, a pair of parallel switches intermediate the source of current and said motor, one of said switches being manually operated and the other switch being a time switch which time switch is adapted to be reset by one of the moving parts of said machine, the timing mechanism of said time switch operating independently of the machine.

5. In a machine of the circulating matrices

type having an electric motor as its motivating means, a pair of parallel switches intermediate the source of current and said motor, one of said switches being manually operated, the other switch being a time switch having a resetting plunger, the timing mechanism of said time switch operating independently of the machine, said time switch being so placed on the machine that the movement of one of the parts of said machine will depress said plunger.

6. In a machine of the circulating matrices type having an electric motor as motivating means, a pair of parallel switches intermediate the source of current and said motor, one of said switches being a manually operated time switch, the other switch being a time switch having a resetting plunger, said switch being so positioned on the machine that the plunger weight lies in the path of an arm of the elevating lever of said machine whereby when said lever is brought into operation said arm will cause the plunger to be depressed, the timing mechanism of the plunger reset time switch operating independently of the machine.

7. In a Ludlow type of line casting machine having an electric motor as motivating means, a pair of parallel switches intermediate the source of current and said motor, one of said switches being adapted to be manually operated, the other switch being adapted to be controlled by a moving part of said machine and being in closed position during the casting operation and in open position at the termination of said operation.

8. In a machine of the circulating matrices type, having an electric motor as its motivating means, a pair of parallel switches intermediate the source of current and said motor, one of said switches being manually operated and the other switch being a time switch, said time switch comprising a timing device and a resetting device, the timing device operating independently of the said machine, said resetting mechanism being operated by a moving part of the said machine.

CHARLES J. RUBB.
